(57) **ABSTRACT**

A combination wristband and label form has a front sheet with a top portion having labels; and a bottom portion having a wristband die cut therein. A portion of the wristband is configured to receive indicia. The form additionally includes a backing sheet comprising a release liner. The wristband has a central portion with a centerline therethrough, separating the central portion into an upper section and a lower section. A first arm portion extends from the upper section in a first direction and a second arm portion extends from the lower section in a second direction. The first and second arm portions have first and second lateral ends, respectively, and the lateral ends each have a respective adhesive area. Removal of the wristband from the form exposes an area of the release liner which is devoid of any voids. The wristband is formed of a single-ply of water-resistant material.

COMBINATION WRISTBAND AND LABEL FORM

RELATED APPLICATIONS

This application is a continuation of U.S. patent application Ser. No. 15/339,105, filed Oct. 31, 2016, which is pending. The '105 Application claims priority to U.S. Provisional Application No. 62/247,863, filed on Oct. 29, 2015, U.S. Provisional Application No. 62/256,465, filed on Nov. 17, 2015, and U.S. Provisional Patent Application No. 62/257,086, filed on Nov. 18, 2015 the disclosures of each of which are incorporated by reference in their entirities herein.

BACKGROUND

The wristband is a frequently-used instrument for distinguishing among various groups of people. For example, wristbands may be used to identify persons in short term healthcare facilities, or to distinguish between levels of access (e.g., at a concert) or permissions. Prior art wristbands often have disadvantages. For example, some wristbands include a paper layer which is not water resistant causing the wristband to become torn and tattered. Other designs include wristbands that are removed from a form such that when the wristband is removed, the form is left with a large void which prevents or makes difficult the ability to pass the remaining labels back through a printer. Thus, there is a need for improved wristbands.

SUMMARY

The following presents a simplified summary of the invention in order to provide a basic understanding of some aspects of the invention. This summary is not an extensive overview of the invention. It is not intended to identify critical elements of the invention or to limit the scope of the invention. Its sole purpose is to present some concepts of the invention in a simplified form as a prelude to the more detailed description presented below.

According to an embodiment, a combination wristband and label form has a front sheet which includes a top portion having a plurality of labels die cut therein; and a bottom portion having a wristband die cut therein. At least a portion of the wristband is configured to receive indicia. The bottom portion further includes a peripheral section. The form additionally includes a backing sheet comprising a release liner. The wristband has a central portion which has a centerline therethrough which separates the central portion into an upper section and a lower section. A first arm portion extends from the upper section in a first direction and a second arm portion extends from the lower section in a second opposing direction. The first and second arm portions have first and second lateral ends, respectively, and the lateral ends each have a respective adhesive area with adhesive attached thereto. Removal of the wristband from the form exposes an area of the release liner which is devoid of any voids. The wristband is formed of a single-ply of water-resistant material.

According to another embodiment, a combination wristband and label form, has a front sheet having a top portion having a plurality of labels die cut therein; and a bottom portion having a wristband die cut therein. At least a portion of the wristband is configured to receive indicia. The bottom portion further comprising a peripheral section. The form further includes a backing sheet having a release liner. The

2

wristband comprises a central portion having a centerline therethrough, separating the central portion into an upper generally transparent section and a lower generally opaque section, and first and second arm portions. The first arm portion extends from the upper section in a first direction and the second arm portion extends from the lower section in a second opposing direction. The first and second arm portions have first and second lateral ends, respectively, each having a respective adhesive area with adhesive attached thereto. The wristband is formed of a single-ply of water-resistant material and is configured for removal from the backing sheet in a single continuous motion. Removal of the wristband from the form exposes an area of the release liner which is devoid of any voids.

According to still another embodiment, a combination wristband and label form has a front sheet; and a backing sheet having a release liner. The front sheet includes a top portion having a plurality of labels die cut therein; and a bottom portion having a wristband die cut therein, at least a portion of the wristband being configured to receive indicia. The bottom portion further includes a peripheral section permanently adhered to the backing sheet. The wristband has a central portion having a centerline therethrough, separating the central portion into an upper, generally transparent section and a lower, generally opaque section. A first arm portion extends from the upper section in a first direction and a second arm portion extends from the lower section in a second opposing direction. The first and second arm portions have first and second lateral ends, respectively, the first and second lateral ends each having a respective adhesive area with adhesive attached thereto, and at least one of the first and second lateral ends has tamper evident slits. The upper, generally transparent section is configured to receive laser printed indicia. Additionally, the wristband is formed of a single-ply of water-resistant material and is configured for removal from the backing sheet in a single continuous motion. Removal of the wristband from the form exposes an area of the release liner which is devoid of any voids. Accordingly, upon removal of the wristband, the form is configured for multiple passes through a printer.

BRIEF DESCRIPTION OF THE DRAWINGS

FIG. 1 is a front side view of a combination wristband and label form according to one embodiment of the invention.

FIG. 2 is a back side view of the combination wristband and label form according to FIG. 1.

FIG. 3 is a back side view of the combination wristband and label form showing an adhesive and silicone pattern according to the embodiment of FIG. 1.

FIG. 4 is a back side view of an alternative embodiment of adhesive and silicone patterns of the form of FIG. 1.

FIG. 5 is a front side view of a combination wristband and label form according to another embodiment of the invention.

FIG. 6 is a back side view of the combination wristband and label form of FIG. 5.

FIG. 7 is a front side view of an alternative embodiment of the form of FIG. 5.

DETAILED DESCRIPTION

Many wristband designs require multiple steps in order to remove the wristband from its liner and subsequently affix it to the wearer. For example, the user may be required to remove the liner in order to expose adhesive. Other wristbands may be configured to include two layers of material,

fastened together with adhesive. The wristband is thus thicker and heavier. Still further designs include a paper layer which is not water resistant that tends to get torn and tattered. According to these designs, a wristband portion is permanently adhered to a paper backing sheet which is die cut in a form, to form a two-layer wristband.

One embodiment of the present invention, described in detail herein, provides for a wristband which may be removed from a form via one generally continuous motion. The wristband may have adhesive on one end only, or on both ends. Further, the wristband may be configured to include only a single layer of a light, synthetic (or other similar) material, thus making the wristband approximately half of the thickness of traditional wristbands currently on the market. Finally, the synthetic material may be water and tear resistant such that the wristband will not tear when removed from the backing sheet prior to affixing the wristband to the person. In one embodiment, the wristband may be configured to be removed from a form without leaving a hole in the form, thus leaving the backing sheet intact such that the form may be passed through a printer multiple times.

With reference now to the figures, FIG. 1 illustrates one embodiment of a combination wristband and label form 100. The form 100 includes a front sheet 101 adhered to a backing sheet 140. The front sheet 101 has a front side 101f and a back side 101b (FIGS. 3 and 4). The front sheet 101 may in some embodiments be separated into a top portion 102 and a bottom portion 103 having a relatively small gap therebetween. The top portion 102 and the bottom portion 103 may each have a front face 102f and 103f, and a back face 102b and 103b, respectively. The top portion 102 and the bottom portion 103 may be separated by a vertical perforation 111.

The front surface 102f of the top portion 102 may include a plurality of labels 107. The labels 107 may be arranged in columns and rows, for example, 4x6. However, the labels 107 may be provided in any combinations of columns (e.g., 1, 2, 3, 4, etc.) and rows (e.g., 1, 2, 3, 4, etc.). The labels 107 may be configured to receive indicia. Accordingly, the front surface 102f may be constructed of paper or other appropriate textile sufficient for receiving ink, e.g., from a printer or other marking device.

The labels 107 may have a variety of constructions. For example, the figures illustrate the labels 107 as having a generally rectangular configuration. However, the labels 107 may be square, circular, polygonal, etc. Additionally, a combination of label configurations may be employed on a single form 100.

The bottom portion 103f may comprise one or more outlines of wristbands 120. The wristbands 120 may include a paper area 105 which is be configured to be printable. In some embodiments, the form 100 may be configured to be passed through a printer so that indicia (e.g., patient name, patient medications, machine readable information such as barcodes, et cetera) may be printed directly on the wristband paper area 105. The paper area 105 may be die cut into the bottom portion 103f. In this manner, the paper area 105 may face the same direction as the labels 107, making it easier for indicia to be simultaneously printed on the labels 107 and the paper area 105.

Attention is now directed to FIGS. 3 and 4, which shows the back side 101b of the form 100. The back side 101b may include a back face 102b of the top portion 102 and a back face 103b of the bottom portion 103. The back face top portion 102b may include an adhesive area 107a. The adhesive area 107a may allow for the labels 107 to be releasably secured to the backing sheet 140. The back face

bottom portion 103b may additionally have an adhesive area 107b. The adhesive area 107b may correspond to the area surrounding the wristband 120 which remains in place when the wristband 120 is removed from the form 100.

The adhesive areas 107a and 107b of the back faces 102b and 103b may adhere to a back side of the backing sheet 140, illustrated in FIG. 2. A top portion 141 of the backing sheet 140 may be constructed of paper or a synthetic resin, and the back side of the top portion 141 (not shown) may include a layer of silicone (or another similar release material) in the area corresponding to the adhesive area 107a. A back side of the bottom portion 142 of the backing sheet 140 may additionally include a layer of silicone in the area corresponding to adhesive area 107b, or may alternatively be permanently adhered to adhesive area 107b (such that the bottom portion 142 does not include a silicone layer). For example, the adhesive area 107a may releasably adhere to the silicone material on top portion 141, and adhesive area 107b may releasably (or permanently) adhere to bottom portion 142 as appropriate. The silicone material may be applied in a pattern which may allow for a more permanent adhesion between the backing sheet 140 and the front sheet 102 in areas void of silicone (e.g., the bond between the area of the bottom portion 142 surrounding the wristband 120 and the back side bottom portion 103b may be stronger than the bond between the top portion 102b and the top portion 141 of the backing sheet 140). This may keep the area of the bottom portion 142 surrounding the wristband 120 in place upon removal of the wristband 120. In some embodiments, the silicone material 107b may be completely omitted so that the area of the bottom portion 142 surrounding the wristband 120 permanently adheres to the back side bottom portion 103b.

As shown in FIG. 3, the back side bottom portion 103b may further include areas of silicone 108 which may coincide with the wristband 120. Additionally, as illustrated in FIG. 4, areas of adhesive 109 may be provided on the areas of silicone 108 to adhere the wristband 120 in place. Alternatively, as described below, adhesive 117, 119, and 135 may be applied to a back side of the backing 142 corresponding to portions of the wristband 120 and/or extension portion 115 in order to adhere the ends 124 and 128 of the wristband 120 together.

FIG. 2 illustrates the backing sheet 140 having a top portion 141 and a bottom portion 142. The wristband 120 may be die cut into the bottom portion 142 of the backing sheet 140, and may be defined by two laterally opposing sides (or ends) 124 and 128 which may extend directly (e.g., without a transition) from a central portion 122 having an upper portion 122a and a lower portion 122b separated by an indentation 123. The laterally opposing sides (or ends) 124 and 128 may extend from the lower portion 122b and the upper portion 122a, respectively (or vice versa).

The sides 124 and 128 extend directly from a central portion 122, without any transition, such as a shoulder, or other type of transition. With such a configuration, the material required for the wristband 120 may be less than otherwise may be required. Further, the design is sleek, having no protrusions or other unneeded and/or unwanted areas of material extending from the central portion 122 and/or the sides 124 and 128.

As noted above, the upper portion 122a (or the lower portion 122b) of the central portion 122 may include a small paper area 105 that is removed from the front sheet 101 along with the wristband 120. The small paper area 105 may leave a small hole in the form 100 after removal therefrom. The wristband 120 may be configured to be self-laminating

to protect the paper area 105. Accordingly, adhesive may be applied to surround the paper area 105 on the central upper portion 122a. Upon removal of the wristband 120 from the form 100, the wristband 120 may be folded about the indentation 123 such that the adhesive on the central upper portion 122a adheres to the central lower portion 122b so that the paper area 105 is secured therebetween. Optionally, adhesive may be applied to the backside of the central lower portion 122b in addition to, or instead of adhesive applied to the backside of the central upper portion 122a.

One of the laterally opposed sides, e.g., side 128, may include perforations 129, and have no adhesive inwardly adjacent the perforations 129. The other laterally opposed side, e.g., side 124, may contain an area of adhesive 135 (FIG. 2) on a backside of the wristband 120, which may be in addition to the adhesive 109 provided on the face sheet portion back side 103b. Alternatively, the adhesive at side 124 may be provided instead of the adhesive 109. The adhesive 135 and/or 109 may keep the end 124 secured to the front sheet back side bottom portion 103b. The wristband 120 may be substantially held into position via the adhesive patch 135 and the perforated side 128. The wristband 120 may contain no adhesive apart from the adhesive 135 adjacent the end 124 and the adhesive surrounding the paper area 105 as described above.

The laterally opposing sides 124 and 128 of the wristband 120 may be generally rectangular. In one embodiment, the sides 124 and 128 are completely straight, without a taper. Alternatively, as shown in the figures, the sides 124 and 128 may gradually taper towards the end and may conclude in a tongue 136. Alternatively, the wristband 120 may take on other desirable shapes. In one embodiment, a height of the tongue 136 (e.g., end 124) may be less than a height of the remainder of the wristband 120 (including being less than the height of the end 128).

The wristband 120 may be further equipped with security slits 130. The security slits 130 may be configured to tear, should the wristband 120 be tampered with after the wristband 120 is applied to a wearer. This may be beneficial to ensure that the wristband 120 remains associated with the intended wearer, particularly in a healthcare environment where the wristband 120 includes patient-specific information.

In addition to the wristband 120, an extension portion 115 may be die cut into the bottom portion 142 of the backing sheet 140 to allow the wristband 120 to accommodate larger wrists. The extension portion 115 may include a first end 116 having an area of adhesive 117 on the backside thereof. A second end 118 may additionally have an area of adhesive 119 on the backside. Adhesive may not be located between the first and second ends of the extension portion 116 and 118, respectively. The second end 118 may additionally include arms 121 extending outwardly from the second end 118, and separated from the second end 118 by lines of perforation 160. Adhesive may be located on the backside of the arms 121. In one embodiment, the arms 121 may be separated from the second end 118 by tearing away at the lines of perforation 160. In another embodiment, the extension second end 118 may be aligned with an end 124 or 128 of the wristband 120 and placed thereupon. The arms 121 may then be folded about the lines of perforation 160, one at a time, to further secured the extension 115 to the wristband 120.

As noted above, the extension portion 115 may attach to either end 124 and 128 of the wristband 120, and may extend the reach of the band 120 by approximately one and one-half inches, for example, although other lengths may

additionally or alternatively be accommodated. Further, the extension may also incorporate tamper evident slits 130.

The bottom portion 142 may be constructed of a synthetic material, such as polyester fabric or plastic, for example. Other materials may additionally, or alternately, be appropriate. Those of skill in the art may recognize that it may be beneficial for the wristband 120 material to be resistant to water or other liquid, which may cause the integrity of the wristband 120 to be prematurely compromised.

In use, after the wristband 120 has been printed, the user may peel the side 124 of the wristband 120 up and away from the form 100, inserting his or her finger under, for example, the bottom edge, until the finger exits at the top edge. The user may then tear the side 128 along the perforations 129 to free the wristband 120 from the form 100. Alternately, the user may hold the wristband 100, e.g., from the top or bottom edge, between his index finger and thumb, tear the side 128 along the perforations 129, and then separate the wristband 120, including the side 124 having the adhesive 119, from the form 100. In this way, the user may remove the wristband 120 from the form 100 in one generally continuous motion. The user may then fold the wristband 120 about the indentation 123 and subsequently attach the wristband 120 to a person's wrist by wrapping the wristband 120 around the wrist, face up, and fastening the adhesive end (e.g., side 124) to the face of the wristband 120. The extension portion 115 may similarly be removed from the form 100 and secured to the wristband 120 as described above.

Such quick and convenient removal of the wristband 120 and/or the extension portion 115 from a single side (e.g., of the backing sheet 140) of the form 100 and its ready securing to a person's wrist may be preferable, as compared for example, to wristbands that must be removed from the associated forms in several steps. This may allow the user to save valuable time, especially where many wristbands 120 are utilized in a single setting. Further, the wristband 120 being removed from a single side of the form 100 eliminates the difficulty of the user having to access both sides of the form 100 in order to push one piece through in order to pull the remainder of the wristband off the form.

Referring now to FIGS. 5-7, an alternative embodiment of a wristband 220 is illustrated which is similar to the wristband 120 except as shown and described herein. Here, the wristband 220 may be die cut into the bottom portion front face 203f, and may be defined by two laterally opposing sides (or ends) 224 and 228 which may extend directly (e.g., without a transition) from a central portion 222 having an upper portion 222a and a lower portion 222b separated by an indentation 223. The laterally opposing sides (or ends) 124 and 128 may extend outwardly from the lower portion 222b and the upper portion 222a, respectively (or from the upper portion 222a and the lower portion 222b, respectively).

The sides 224 and 228 may be generally rectangular, and may be completely straight. Optionally, the sides 224 and 228 may taper away from the central portion 222 and conclude in a tongue 226, similar to the wristband 120 described above. One or both ends 224 and 228 may include tamper evident slits 214, configured to tear should the wristband 220 be tampered with after the wristband 220 is applied to the wearer.

The lower portion 222b (or the upper portion 222a as the case may be) of the central portion 222 may include a small laser printable area 205 which may allow indicia to be printed on the wristband 220 without having to provide a paper area. Further, the laser printable area may allow for the

wristband 220 to be removed from the form 200 without leaving a hole in the form 200.

An extension band 215, substantially similar to extension band 115 may additionally be included with the wristband 220 on the front face bottom portion 203b.

Referring now to FIG. 6, which illustrates a back side 201b of the form 200, adhesive areas 207a and 207b may be provided. It may be advantageous to additionally have areas 208 without adhesive. The adhesive areas 207a and 207b may adhere to a backing sheet which may be made of, for example, paper or synthetic resin and may be generally similar to back sheet 140. The backing sheet may include silicone or other suitable release material on the side of the backing sheet which contacts the adhesive areas 207a and 207b. This may thus allow the top portion 202 and bottom portion 203 to be releasably adhered to the backing sheet. As can be seen by comparing FIGS. 5 and 6, the area of adhesive 207b may be such that it encompasses a portion of the sides 224 and 228, and further such that adhesive is provided around the perimeter(s) of the central upper and lower portions 222a and 222b.

The configuration of the wristband 220 on the form 200 may be such that the adhesive ends 224 and 228 are initially all facing the same direction (e.g., toward the backing sheet). Upon folding the wristband 220 about the indentation 223, the adhesive covered ends 224 and 228 may face in opposite directions such that they meet back to back, thus forming a solid adhesion to the wristband 220 (or the extension portion 215) and not exposing the adhesive to the patient.

In use, a user may peel the wristband 220 from the form 200, wherein the adhesive remains at the desired location on the underside of the wristband. The wristband 220 may be peeled from the form 200 in a similar manner as that described above regarding wristband 120. Specifically, a user may insert his or her finger under the wristband 220 from the bottom edge, the finger exiting under the top edge. The user may then slide his or her finger toward one of the ends (e.g., end 228) to release the adhesive under the end 228 from the backing. The user may then grasp the end (e.g., 228) and peel the rest of the wristband 220 from the backing. Therefore, as with the wristband 120, the wristband 220 may similarly be pulled from a single side of the form 200.

When the wristband 220 is removed from the form 200, the area of the backing sheet behind the wristband 120 may remain intact. Such a configuration may provide several benefits over prior art wristbands. For example, as noted above, other methods may consist of “punching out” the wristband from the form leaves a void that may prevent the rest of the form from being used at a later time. However, if the form remains intact, as in the present invention, it may be used multiple times, for example, to print on the labels 207. This may be beneficial because it is often desirable to print the labels 207 at different times (for example, it may be desirable to print new labels 207 to reflect changes made to medications prescribed to a patient during the course of his treatment). A new label 207, such as a label 207 leftover on the form 200, may thus be printed with the new information until all the labels 207 have been used. Of course, the labels 207 may be used for any desirable purposes, such as for labeling patient files and other documents, vials, etc. The labels 207 may all be printed with information in a single pass through the printer, or the form 200 may be passed through the printer multiple times such that the labels 207 are printed as needed.

In another embodiment, illustrated in FIG. 7, a form 300 may consist of a plurality of wristbands 320 (which may be wristband 120, 220, or another alternative wristband) and

does not include labels 107 and 207. Alternately, a form may include only a single wristband. The form 300 may be approximately the size of a standard piece of paper (e.g., 8½"×11"), or the form may be tailored to the size of the required wristbands and/or labels. For example, if only a single wristband is required, the form may be only the size necessary to contain one wristband.

Many different arrangements of the described invention are possible without departing from the spirit and scope of the present invention. Embodiments of the present invention are described herein with the intent to be illustrative rather than restrictive. Alternative embodiments will become apparent to those skilled in the art that do not depart from its scope. A skilled artisan may develop alternative means of implementing the disclosed improvements without departing from the scope of the present invention.

Further, it will be understood that certain features and subcombinations are of utility and may be employed without reference to other features and subcombinations and are contemplated within the scope of the claims. Not all steps listed in the various figures and description need to be carried out in the specific order described. The description should not be restricted to the specific described embodiments.

The invention claimed is:

1. A combination wristband and label form, comprising: a front sheet comprising:

a top portion having a plurality of labels die cut therein; and

a bottom portion having a wristband die cut therein, at least a portion of the wristband being configured to receive indicia; the bottom portion further comprising a peripheral section;

a backing sheet comprising a release liner; and wherein the wristband comprises a central portion having a centerline therethrough separating the central portion into an upper section and a lower section, and first and second arm portions, wherein the first arm portion extends from the upper section in a first direction and the second arm portion extends from the lower section in a second opposing direction, and wherein the first and second arm portions have first and second lateral ends, respectively, the lateral ends each having a respective adhesive area with adhesive attached thereto; and

wherein:

removal of the wristband from the form exposes an area of the release liner, the area being devoid of any voids;

adhesive is attached along a perimeter of the upper section and the lower section of the central portion, adhesive not being located inside the perimeter of the upper section and the lower section;

indicia is deposited on one of the upper section and the lower section of the central portion;

the central portion is foldable about the centerline such that the indicia is not covered by the other of the upper section and the lower section of the central portion; and

the wristband is formed of a single-ply of water-resistant material.

2. The combination wristband and label form of claim 1, wherein at least one of the first and the second lateral ends is equipped with tamper evident slits.

3. The combination wristband and label form of claim 2, wherein the wristband first and second arm portions each

comprises two longitudinal edges; each of the longitudinal edges being defined by the die cut in the front sheet bottom portion.

4. The wristband and label form of claim 3, wherein each of the longitudinal edges define a gap between the wristband and the release liner. 5

5. The combination wristband and label form of claim 4, wherein the wristband is configured to be removed in a single continuous motion from the backing sheet bottom portion, the adhesive areas on the respective first and second lateral ends being immediately exposed upon removal of the wristband from the front sheet bottom portion. 10

6. The combination wristband and label form of claim 5, wherein the portion of the wristband configured to receive indicia is a laser printing portion. 15

7. The combination wristband and label form of claim 6, wherein:

the laser printing portion is located at either the upper section or the lower section;

the laser printing portion is substantially transparent; and the other of the upper section or the lower section is substantially opaque. 20

8. The combination wristband and label form of claim 7, wherein the central portion is foldable about the centerline such that the indicia on the laser printing portion becomes viewable. 25

9. The combination wristband and label form of claim 1, wherein the front sheet bottom portion further comprises a extension portion die cut therein, the extension portion comprising first and second spaced apart ends, the first spaced apart end having first and second arms extending outwardly therefrom and separated from the first spaced apart end via perforations; wherein the first and second spaced apart ends and the arms each have adhesive adjacent thereto. 30

10. The combination wristband and label form of claim 9, wherein removal of the extension portion immediately exposes the adhesive on the first and second spaced apart ends. 35

11. The combination wristband and label form of claim 10, wherein at least one of the first and the second spaced apart ends is equipped with tamper evident slits. 40

12. A combination wristband and label form, comprising: a front sheet comprising:

a top portion having a plurality of labels die cut therein; 45 and

a bottom portion having a wristband die cut therein, at least a portion of the wristband being configured to receive indicia; the bottom portion further comprising a peripheral section;

a backing sheet comprising a release liner; and wherein the wristband comprises a central portion having

a centerline therethrough separating the central portion into an upper generally transparent section and a lower generally opaque section, and first and second arm portions, wherein the first arm portion extends from the upper section in a first direction and the second arm portion extends from the lower section in a second opposing direction, and wherein the first and second arm portions have first and second lateral ends, respectively, the lateral ends each having a respective adhesive area with adhesive attached thereto; and

wherein:

the wristband is formed of a single-ply of water- 55 resistant material;

the wristband is configured for removal from the backing sheet in a single continuous motion;

indicia is deposited on one of the upper section and the lower section of the central portion;

the central portion is foldable about the centerline such that the indicia is not covered by the other of the upper section and the lower section of the central portion;

adhesive is attached along a perimeter of the upper section and the lower section of the central portion, adhesive not being located inside the perimeter of the upper section and the lower section; and

removal of the wristband from the form exposes an area of the release liner, the area being devoid of any voids.

13. The combination wristband and label form of claim 15 12, wherein at least one of the first and the second lateral ends is equipped with tamper evident slits.

14. The combination wristband and label form of claim 13, wherein the indicia is printed on the upper generally transparent portion, and wherein, upon removal from the 20 form, the wristband is folded about the centerline, the lower generally opaque portion allowing the indicia to be easily viewed.

15. The combination wristband and label form of claim 12, wherein the peripheral section is permanently adhered to the 25 backing sheet.

16. The combination wristband and label form of claim 15, wherein the front sheet bottom portion further comprises a extension portion die cut therein, the extension portion comprising first and second spaced apart ends each having adhesive adjacent thereto. 30

17. The combination wristband and label form of claim 16, wherein removal of the extension portion immediately exposes the adhesive on the first and second spaced apart ends, and wherein at least one of the first and second spaced apart ends is equipped with tamper evident slits. 35

18. The combination wristband and label form of claim 15, wherein, in a use configuration, the wristband is removed from the form in a single continuous motion, and subsequently folded about the centerline such that the adhesive areas on the respective lateral ends face in opposing directions such that it is configured to be attached to a recipient. 40

19. The combination wristband and label form for claim 18, wherein the form is configured for multiple passes through a printer. 45

20. A combination wristband and label form, comprising: a front sheet; and a backing sheet having a release liner; wherein the front sheet comprises:

a top portion having a plurality of labels die cut therein; and

a bottom portion having a wristband die cut therein, at least a portion of the wristband being configured to receive indicia; the bottom portion further comprising a peripheral section permanently adhered to the backing sheet;

wherein the wristband comprises a central portion having a centerline therethrough separating the central portion into an upper, generally transparent section and a lower, generally opaque section, and first and second arm portions, wherein the first arm portion extends from the upper section in a first direction and the second arm portion extends from the lower section in a second opposing direction, and wherein the first and second arm portions have first and second lateral ends, respectively, the first and second lateral ends each having a respective adhesive area with adhesive attached thereto; and

wherein:

11

at least one of the first and second lateral ends has tamper evident slits;
the upper, generally transparent section is configured to receive laser printed indicia;
adhesive is attached along a perimeter of the upper 5 section and the lower section of the central portion, adhesive not being located inside the perimeter of the upper section and the lower section;
the central portion is foldable about the centerline such that the indicia is not covered by the generally 10 opaque section;
the wristband is formed of a single-ply of water-resistant material;
the wristband is configured for removal from the back-
ing sheet in a single continuous motion; 15
removal of the wristband from the form exposes an area of the release liner, the area being devoid of any voids; and
upon removal of the wristband, the form is configured for multiple passes through a printer. 20
